DESIGN FOR ORNAMENTATION OF SEWING-MACHINES.

SPECIFICATION forming part of Design No. 13,879, dated May 1, 1883.

Application filed March 24, 1883. Term of patent 7 years.

UNITED STATES PATENT OFFICE.

WILLIAM HAEHNEL, OF NEW YORK, N. Y., ASSIGNOR TO CHARLES PALM
AND JULIUS FECHTELER, OF SAME PLACE.

DESIGN FOR ORNAMENTATION OF SEWING-MACHINES.

SPECIFICATION forming part of Design No. 13,879, dated May 1, 1883.

Application filed March 24, 1883. Term of patent 7 years.

To all whom it may concern:

Be it known that I, WILLIAM HAEHNEL, of New York, in the county and State of New York, have invented a new and original Design for Ornamentation of Sewing-Machines, of which the following is a specification.

This invention relates to a new and original design for the ornamentation of sewing-machines and other articles; and it consists in the novel grouping and configuration of figures hereinafter more fully described.

The accompanying illustrations show in Figure 1 a view of a sewing-machine plate and arm having thereon my new design. Fig. 2 is an enlarged detail view of the ornamentation of the cloth-plate. Fig. 3 is an enlarged detail view of the ornamentation of the back of the post of the sewing-machine arm. Fig. 4 is an enlarged detail view of the ornamentation at the front of the post of the sewing-machine arm. Fig. 5 is an enlarged detail view of the ornamentation at the side of the post of the sewing-machine arm. Fig. 6 is an enlarged detail view of the ornamentation of the back portion of the side of the sewing-machine arm. Fig. 7 is an enlarged detail view of the ornamentation along the side of the sewing-machine arm.

The figure A ornaments the cloth-plate of the sewing-machine, and consists of the number "10," or other number or mark, surrounded by a wreath apparently composed of leaves, which wreath in turn is surrounded by an outside circular figure made up of curving scroll-work.

The figure B ornaments the stem or supporting-post of the needle-arm on its inner face, and consists of a triangular figure built up of scroll-work.

The figure C ornaments one side of the post supporting the sewing-machine arm, and consists of a circle made up at its lower part of a wreath and at its upper part of scroll-work, which may inclose a medallion, trade-mark, or similar device.

The figure D ornaments the back of the post of the sewing-machine arm, and consists of scroll-work branching out on each side and terminating in flowers and leaves, with an open-

ing in the middle for the insertion of a number or device.

The figure E ornaments the side of the sewing-machine arm, on the back portion thereof, and consists of a curving bar with the scroll-work and tendrils surrounding it.

The figure F, which ornaments the sewing-machine arm along its side, is composed of scroll-work with a slender tendril running out from one side thereof, within which is placed the inscription "Wheeler & Wilson," or other inscription upon the side of the sewing-machine arm.

I claim—

1. The design for the ornamentation of sewing-machines, consisting of the figure A, substantially as shown. 65

2. The design for the ornamentation of sewing-machines, consisting of the figure B, substantially as shown.

3. The design for the ornamentation of sewing-machines, consisting of the figure C, substantially as shown. 70

4. The design for the ornamentation of sewing-machines, consisting of the figure D, substantially as shown.

5. The design for the ornamentation of sewing-machines, consisting of the figure E, substantially as shown. 75

6. The design for the ornamentation of sewing-machines, consisting of the figure F, substantially as shown. 80

7. The design for the ornamentation of sewing-machines, consisting of the figures B and C, substantially as shown.

8. The design for the ornamentation of sewing-machines, consisting of the figures F and E, substantially as shown. 85

9. The design for the ornamentation of sewing-machines, consisting of the figures B, C, E, and F, substantially as shown. 90

10. The design for the ornamentation of sewing-machines, consisting of the figures A, B, C, D, E, and F, substantially as shown.

WILLIAM HAEHNEL.
